NERVE PRESSURE METER

Colin D. Murdoch, San Leandro, Calif.

Application March 19, 1953, Serial No. 24,105

Term of patent 14 years

(Cl. D52—1)

Fig. 1

Fig. 2

Fig. 3

To all whom it may concern:

Be it known that I, Colin D. Murdoch, a citizen of the United States of America, residing at San Leandro, in the county of Alameda, State of California, have invented a new, original, and ornamental Design for a Nerve Pressure Meter, of which the following is a specification, reference being had to the accompanying drawings, forming part thereof.

Figure 1 is a perspective view of a nerve pressure meter embodying my new design,

Figure 2 is a plan view of the same nerve pressure meter, and

Figure 3 is a side elevation of the nerve pressure meter.
I claim:

The ornamental design for a nerve pressure meter, substantially as shown.
